UNITED STATES PATENT OFFICE.

HUBERT A. MYERS, OF TOLEDO, OHIO.

AUTOMOBILE WINDOW LIFTER.

Application filed February 5, 1923. Serial No. 616,926.

To all whom it may concern:

Be it known that I, HUBERT A. MYERS, a citizen of the United States, and a resident of Toledo, in the county of Lucas and State of Ohio, have made an Invention Appertaining to Automobile Window Lifter, which invention is fully set forth in the following specification.

My invention has for its object to provide an efficient easily operated device for raising and lowering particularly windows of automobiles that may be made at a low cost of production. This invention also provides an automatic locking device for securing the window in the position in which it is placed, the locking device automatically releasing the window upon operation of the manual means used for manipulating the device and automatically engaging upon cessation of the movement of the said manual means. The invention also has for its object to produce an exceedingly simple counter-balancing device for counter-balancing the window, that is, a part or all of its weight that operates through the lifting device which securely holds the interconnecting parts in contact and thus prevents rattling and enables easy operating the device in raising and lowering the window. The invention also has for its object other features and advantages that will appear from the following description and upon examination of the drawings.

The invention may be contained in structures of different forms. To illustrate a practical application of the invention I have selected one of the structures containing the invention and shall describe it hereinafter. The structure selected is illustrated in the accompanying drawings.

Figure 1 of the drawings illustrates an edge view of the lifting device, the frame and window being shown in section. Fig. 2 is a side view of the frame. Fig. 3 is a sectional view taken on the line 3-3 in Fig. 2. Fig. 4 is a sectional view taken on the line 4-4 indicated in Fig. 3. Fig. 5 is a sectional view taken on the line 5-5 indicated in Fig. 3. Fig. 6 is a sectional view taken on the line 6-6 indicated in Fig. 5. Fig. 7 is a sectional view taken on the line 7-7 indicated in Fig. 4. Fig. 8 is a sectional view taken on the line 8-8 indicated in Fig. 3. Fig. 9 is a sectional view taken on the line 9-9 indicated in Fig. 3, and Fig. 10 illustrates a perspective view of a part of the

automatic clutch for securing the lifting device. Fig. 11 illustrates a sectional view, and Fig. 12 illustrates a side of a modification of the means for securing the window in any position to which it may be moved by the lifting device.

The window lifting device may be used in any part of the automobile body frame for raising any windows of the automobile, that is, it may be used for opening and closing the windows of the doors, or those that are located in the body of the car. In Figs. 1 and 2, 1 indicates a supporting or guiding frame, such as the frame of a door of the automobile and in which the window is guided in its vertical movements by suitable guiding channels or strips 2.

The window 3 is provided with the usual metallic frame 4 that may extend around the side edges and the bottom edge or may extend merely across the bottom edge of the window. The strip 4 may be made in the form of a deep channel. One edge may be bent outwardly with respect to the window, as at 5, to form an engaging lip. A bent bar 6 is connected to the lifting device so as to be moved thereby. The bar 6 extends from within the plane of the inner surface of the window to the outer surface of the channel 4. The bar is provided with an elastic hook 7 formed of sheet metal having an engaging nose 8 for engaging the inner edge of the channel 4. The spring or elastic member 7 is preferably made broad so as to have a broad engaging edge or nose 8, as shown in Fig. 5. The engaging nose 8 is preferably formed of two parts that are spaced from each other leaving an end edge 9 along the top of the spring member 7 and along the top of the inner edge of the channel 4 and so that an instrument, such as a screw driver, may be inserted between the edge 9 and the inner edge of the channel 4 and turned so as to move the engaging nose 8 from the inner edge of the channel 4 and thus release the window from the elastic hook 7. This provides an exceedingly simple means for connecting the window to the lifting device. The window is merely inserted between the bent bar 6 and the elastic hook 7 and is depressed until the upper end of the bar 6 rests against the engaging lip 5 of the channel 4. When in this position the nose 8 of the elastic hook 7 passes over the inner edge of the channel 4 and thus holds the window down and so as to

hold the engaging lip 5 against the end of the bar 6. When it is desired to remove the window all that is necessary is to insert an instrument between the elastic member 7 and the channel bar or frame 4 and raise the window so as to raise the inner edge of the channel bar above the engaging nose 8 of the spring 7.

The bar 6 and consequently the window 3 is connected to the lifting device by means of a pair of bolts or pins 9 that extend through two rollers 10. The rollers 10 are located on the opposite sides of a twisted strip 11 that is preferably formed of band 15 steel and twisted to produce two opposite lateral spiral surfaces having the width of the band from which the spiral is formed. The rollers are so located that their inner contacting surfaces will be positioned apart 20 substantially the thickness of the band. The surfaces of the rollers are preferably barrel shape and have flaring end edges so as to conform as much as possible to the shape of the lateral surfaces and corners of the 25 spiral along the lines of contact between the rollers and the lateral surfaces of the spiral. The pins 9 are secured in position by means of the flanges or bosses 12 formed on the pins and the nuts 13. The rollers 10 freely 30 rotate on the pins 9 as they are moved along the spiral 11.

The spiral 11 is secured at its upper end to a spindle 14 and at its lower end to a cylindrical block 15. The spindle 14 and 35 the block 15, and consequently the spiral 11, are pivotally supported in a frame 16. The frame 16 may be formed of a sheet metal strip bent to form the sides of an oblong box having an opening 17 in one side, along 40 which the rollers 10 are moved by the spiral 11. The bar 6 extends over the edges of the opening 17 and a strip or plate 18 is located between the edges of the opening 17 and the bar 6 and so as to practically cover the portion 45 of the opening that may be located between the bar 6 and the spiral. The plate 18 is secured in position by means of the pins 9 through which they extend, the plate 18 and the bar 6 being clamped together by 50 means of the nuts 13. The ends of the oblong frame or box 16 are provided with metal blocks 19 and 20 that close the ends of the box. The spindle 14 has a bearing in the block 19 and the block 15 is stepped 55 in the block 20. Balls or rollers 21 may be located between the block 15 and the block 20 to support the end thrust of the spiral 11 and at the same time permit pivotal movements of the spiral. 60 A worm-wheel 22 is connected to the spindle 14. The worm-wheel meshes with the worm-wheel 23, the axes of the two worm-wheels being located at right angles to each other. A crank handle, such as the 65 handle 24, is connected to the worm-wheel

23 by means of the shank or pin 25. The handle 24 is supported for rotating movements in a part of the frame 1, as illustrated in Fig. 2. Rotation of the crank 24 thus causes rotation of the spiral 11 which causes 70 the lateral surfaces of the spiral to engage the rollers and move the rollers along the spiral either up or down or according to the direction of rotation of the crank 24. Preferably the direction of the thread of 75 the worm-gears 22 and 23 is such that when the window is being lifted, the friction between the worm-gear will tend to lift the spiral 11 which will reduce the load or pressure on the balls or rollers 21. 80

To counter-balance the effect of the weight of the window on the lifting device, a means is provided for yieldingly resisting the rotation of the spiral 11 due to the weight of the window. A sleeve 26 is located on the spindle 14 and a long spring wire 27 surrounds the sleeve 26. One end of the wire 27 is secured in position by the pin 28 and the other end of the spring is connected to the spiral gear 22. One end of the spring 27 is rotated sufficiently and in such a direction as to counter-balance the rotation of the spiral 11 due to the weight of the window operating through the roller 10. This prevents the window from moving down the spiral by its own weight and causing the spiral to rotate. It thus prevents normally the dropping or lowering of the window. The spring wire 27 is a long spring wire and consequently may be rotated through quite 100 a range of turns without materially affecting the counter-balancing effect of the spring, so that the window will be held in whatever position it is placed by the rotation of the crank 24, which causes the rollers 105 to move along the spiral 11.

Since the spring 27 is merely a counter-balancing spring it will not prevent the window from lowering when it is jarred down, which occurs when the automobile is 110 running over the road. In order to securely hold the window in any position in which it is placed by the operation of the spiral 11, I have provided an automatic clutch or locking device. A cylindrical block 29 is secured 115 to the oblong box 16. It surrounds the hub of the gear-wheel 23. The hub of the gear-wheel 23 freely rotates in the cylindrical block 29. A cylindrical shell 30 surrounds and substantially covers the cylindrical 120 block 29 except at one side which is provided with an opening through the flange of the shell. A coiled spring or band 31 is located around the cylindrical block 29 and within the shell 30. The spring is tightly 125 drawn and engages the end edges of the flange of the shell in the opening. The cylindrical block 29 is thus elastically engaged by the spring and the shell 30 is normally held in position relative to the block 29 by 130

the protruding ends of the wire 31. The shell 30 is keyed to the gear 23, the hub of the gear 23 having a square end which fits a square opening formed in the end of the shell. A disk 32 is keyed to the spindle or shank 25, the spindle 25 being provided with a square shoulder 33 that fits a square opening formed in the central part of the disk 32. The disk 32 has a finger 34 that is bent over the shell 30 and is located between the protruding ends of the wire 31. When, therefore, the handle 24 is rotated, it rotates the disk 32, which is keyed to the handle through the spindle 25. The finger 34 is thus moved to the right or left according to the rotation of the handle, and is caused to engage one of the protruding ends of the wire. This tends to unwind the wire from the block 29 and thus loosens the grip of the wire and at the same time the pressure on one end of the spring by the finger 34 is transmitted to the edge of the opening of the shell 30 on the side of the finger in the direction in which it is turned by the handle, which causes the shell 30 to rotate and consequently causes the gear-wheel 23 to rotate and consequently the window is raised or lowered according to the direction in which the handle 24 is turned. When the pressure of the finger 34 against either end of the spring 31 ceases, that is, when the rotation of the handle is discontinued, the spring immediately grips the cylindrical block 29 and holds the shell 30 in the position that it is placed relative to the block and thus the gear 23 is securely locked. This prevents the window from being lowered by such jolting as might overcome the balancing spring 27.

In the modification shown in Figs. 11 and 12 the clutch operates directly on the spiral 11 and its engagement is controlled by movement of one of the gear wheels. The finger 36 is connected to the spiral gear wheel 37 which is keyed to the spindle 38. The counter-balancing spring 27 is connected to the gear wheel 37 in the same manner that it is connected to the gear wheel 22 in the form illustrated in Figs. 3 and 4, and operates in the same way. A cylindrical member 39 is secured to a part of the container or oblong box 16. The fixed cylindrical member 39 also forms a bearing for the block 40 which is connected to the upper end of the spiral band 11. The second cylindrical member or cup 41 is keyed to the block 40 and is thus connected to the spiral band 11. The wire band 42 is constructed and located with reference to the cylindrical members 39 and 41 the same as in the structure shown in Fig. 3, the member 41 having an opening 43 on one side thereof through which the ends 44 of the

band spring protrudes. The finger 36 is located between the ends 44 of the spring 42 and so that when the spiral gear 23 is rotated it will rotate the spiral gear 37 and move the finger 36 to the right or the left to engage one of the ends 44 of the spring 42 and thus tend to unwind or loosen the spring in its engagement between the edges of the opening 43 and the cylindrical member 39, which will at the same time rotate the spiral 11 to raise and lower the window. When the spiral gear 23 ceases to rotate the engagement is made between the fixed member 39 and the cup 41 which locks the spiral band in position and thus locks the window. The balancing spring 27 also operates through the spiral gear 37, but the force or pressure produced by the balancing spring 27 is not sufficiently great to cause the rotation of the spiral band 11, but is sufficiently great to prevent the rotation of the band 11 by reason of the weight of the window.

I claim:—

1. In a window lifting device, a spiral metal band, rollers connected to the window, a rotatable member for rotating the spiral band and a clutch mechanism controlled by the rotatable member for locking the window.

2. In a window lifting device, a vertical rotatable member connected to the window for raising and lowering the window, means for rotating the vertical rotatable member a locking device for locking the rotatable member in position, a counter-balancing spring directly connected to the rotatable member for counter-balancing the window.

3. In a window lifting device, a spiral band for raising and lowering the window, a rotatable member for operating the spiral band, a locking device for locking the rotatable member, a counter-balancing spring connected to the spiral band for counter-balancing the weight of the window.

4. In a window lifting device, a window supporting structure, a screw member, a means for actuating the screw member, a member connecting the window with the screw member for actuating the window, a locking means for securing the window in the position into which it is moved and connected to the screw member for locking the screw member against rotation, a removable frame for supporting the screw member, the locking means and the actuating means and for guiding the connecting means and means for securing the frame in position in the window supporting structure.

In testimony whereof I have hereunto signed my name to this specification.

HUBERT A. MYERS.
